UNITED STATES PATENT OFFICE.

ARTHUR R. MASON AND OTTO C. FAILING, OF MEDFORD, OREGON, ASSIGNORS TO ACCURATE GASOLINE RECORDING COMPANY, A CORPORATION OF OREGON.

RECORDING AND SALES-CHECK MECHANISM FOR FLUID-DISPENSING PUMPS.

Application filed August 16, 1926. Serial No. 129,614.

The invention relates to means whereby the customer and salesman each receives a check showing the amount of fluid dispensed at each sales transaction, the salesman's check being preferably retained and wound into a roll for convenient and ready reference.

One of the purposes of the invention is to eliminate, as much as possible, the leakage, or error attributable to dishonesty or neglect in making charges, and to insure full measure to the customer in the amount noted on the check.

A further purpose of the invention is the provision of a mechanism of the character aforesaid which may be readily applied to a fluid dispensing pump, such as generally employed at service stations, for supplying motor fuel and oil in measured quantity.

The invention further aims to provide a mechanism which is simple, efficient and readily accessible, the working parts being mounted upon a plate which is readily insertable in a casing, and easily removable therefrom as occasion may require.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is an elevational view of a fluid dispensing pump provided with recording and sales check mechanism embodying the invention.

Figure 2 is a front view of the mechanism showing the parts on a larger scale and the casing in section.

Figure 3 is a fragmentary sectional view on the line 3—3 of Figure 2, looking to the left, as indicated by the arrows.

Figure 4 is a sectional view on the line 4—4 of Figure 2, looking to the right, as indicated by the arrows.

Figure 5 is a fragmentary sectional view on the line 5—5 of Figure 3.

Figure 6 is a sectional view of the feed

roll for the recording and sales check strip, on the line 6—6 of Figure 2. 55

Figure 7 is a sectional view of the spool for the strip roll and the spindle therefor, on the line 7—7 of Figure 2.

Figure 8 is a sectional view of the spool upon which the retained portion of the strip is wound and the spindle therefor, on the line 8—8 of Figure 2. 60

Figure 9 is a fragmentary perspective view of a portion of the plate and bracket forming supporting means for the operating 65 mechanism, and

Figure 10 is a detail view of a portion of the recording and sales check strip.

Corresponding and like parts are referred to in the following description and designated in the several views of the drawings by like reference characters. 70

The operating parts of the mechanism are enclosed within a casing designated by the numeral 10 which is open at one side to which is fitted a door 11 which, when closed, is made secure by a suitable lock mechanism to prevent surreptitious entry to the casing and a possible tampering with the mechanism. The front of the casing is provided with a delivery slot 12 for the discharge of a portion of the strip corresponding to the sales check for the customer. Blocks 13 are located at the four corners of the casing adjacent the side opposite that closed by means of the door 11 and these blocks may form a part of the casing and provide convenient means for supporting a plate 14 which is bolted, or otherwise attached thereto, said plate being readily removable from the casing and constituting a frame for receiving and supporting the operating parts of the mechanism. Similar brackets 15 and 16 are attached to opposite sides of the plate 14 and project in opposite directions therefrom adjacent the top of the casing 10. The upper edge of the plate 14 is notched to receive the horizontal portions of the brackets 15 and 16, as shown most clearly in Figure 9. The bracket 16 is located near the front 100

of the casing, whereas the bracket 15 is located near the back of the casing. The end portions of the brackets remote from the plate 14 extend downwardly, as shown most clearly in Figure 2, and provide convenient 105 means for supporting parts of the mech-

anism which are journaled therein. A shaft 17 journaled in the bracket 15 extends through a side of the casing 10 and is adapted to be coupled to an operating part 5 of the fluid dispensing pump. A disk or plate 18 is made fast to the inner end of the shaft 17 so as to rotate therewith. A plurality of pawls 19 are mounted upon the plate 18 and are adapted to coact with a 10 spur wheel 20 loose upon the shaft 17, whereby to effect rotation of the shaft and spur wheel in one direction. A bevel gear 21 rotatable with the spur gear 20 and preferably forming a part thereof, is in mesh with a 15 bevel pinion 22 fast to the adjacent end of a worm shaft 23 which is mounted in bearings 24 secured to the plate 14, endwise movement of the shaft being prevented by having the ends of the worm 23 engaging 20 the brackets 24, as shown most clearly in Figure 3. The worm 23 is in mesh with a worm gear 25 fast to one end of a shaft 26 which is journaled at one end in the plate 14 and at its opposite end in the depending 25 portion of the bracket 16. The shaft 26 receives a feed roll 27 which is clamped between cones 28 and 29 disposed at opposite ends of the shaft 26, the cone 28 preferably forming a part of the shaft and the cone 30 29 forming part of a nut 30 which is threaded upon an end of the shaft 26. By loosening the nut 30 the feed roll 27 may be rotated upon the shaft 26 to admit of a new recording and sales check strip being placed 35 in position or adjusted, as required. When the nut 30 is tightened the feed roll 27 is clamped and caused to rotate with the shaft 26. The feed roll 27 is provided with a medial groove 31 to coact with a rotary cutter 32 for severing the strip longitudinally. The feed roll 27 is also provided with spur teeth 33 which mesh with the teeth of a spur gear 34 fast to the shaft 35 which carries the rotary cutter 32. An end portion of 40 the feed roll 27 is grooved to receive a drive belt 36 which transmits motion to the spool 37 upon which the retained portion of the strip is wound. Teeth 38 are provided at opposite ends of the feed roll 27 and make positive engagement with the recording and sales check strip which, as shown in Figure 45 10, is provided along opposite edges with openings 39 which are engaged by the teeth 38.

50 The shaft 35 is journaled at one end in the plate 14 and at its opposite end in the depending portion of the bracket 16. The rotary cutter 32 is fast to the shaft 35 and is adapted to coact with the feed roll 27 to sever the strip 40 longitudinally, to form the sales check portion and the recording portion, the latter being preferably wound upon the spool 37, whereas the sales check portion is divided to admit of each customer 55 receiving a check indicating the purchase.

The spur gear 34 transmits motion to the shaft 35 from the shaft 26. Grooved rollers 42 fast to the shaft 35 coact with the teeth 38 of the feed roll 27 to prevent disengagement of the strip 40 from the toothed portion of the feed roll and in consequence, the strip 40 can not be moved independently of the feed roll, and the latter cannot be moved without effecting a corresponding movement of the strip 40.

A spindle 43 is secured at one end to the plate 14, as shown most clearly in Figure 7, and receives the roll resulting from reeling the strip 40. The spool mounted upon the spindle 43 comprises a body 44 and heads 45, one end of the body 44 being reduced and threaded to receive a nut 46 and the opposite end of the body having a head 47. The core or center 48 upon which the strip 40 is wound is slipped upon the body 44 of the spool and is clamped between the heads 45, it being understood that the nut 46 and the adjacent head 45 is removed to admit of placing the roll upon the spool, after which the nut 46 and heads 45 are replaced. The roll is adapted to turn with the spool upon the spindle 43, the strip 40 being drawn from the roll by the member 27.

The spool 37 is loosely mounted upon a spindle 49 which is secured at one end to the plate 14 in a manner similar to the spindle 43. This spool includes a center or core 37 upon which the retained portion of the strip 40 is wound and which constitutes the record of the station. The part 37 is 50 formed with a slot 50 through which an end portion of the strip is passed, whereby to provide connection between the strip and spool, so that when the latter is rotated the strip will be wound thereon. The numeral 100 51 designates the body of the spool, and 52 are heads clamped thereto by means of a nut 53 threaded upon a reduced end portion of the body 51. An end portion of the spool body 51 is grooved to receive the drive 105 belt 36 by means of which motion is transmitted from the shaft 26 to the rewinding spool. The head of the spool body 51 is provided with lateral projections 54 to make positive engagement with the center or core 37 to insure rotation of the latter and the winding of the recording or retained portion of the strip 40. An idle roll 55 is positioned to one side of the spools 48 and 37 to give proper direction to the strip 40 to prevent interfering thereof with the parts of the strip wound upon either of the said spools. The guide roller 55 is mounted upon a spindle 56 which is secured at one end to the plate 14 in a manner similar to the 110 spindles 43 and 49.

The numeral 57 designates a dispensing pump, such as generally provided at service stations for supplying motor fuel and lubricating oil in measured quantity. The 120 125 130

5 numeral 58 designates the usual delivery tube. In accordance with the present invention, the projecting end of the shaft 17 is adapted to be coupled to the operating shaft 59 of the pump in any determinate way, so that the two shafts 59 and 17 turn in unison. The pump is of the type provided with the usual rack 60 and pinion 61 whereby the pump is operated upon rotation of the operating shaft 59 in the accustomed manner. Rotation of the operating shaft 59 causes a corresponding movement of the shaft 17 and feed roll 27, whereby a portion of the strip 40 is drawn from the roll and projected 10 through the delivery slot 12. When a portion of the strip 40 is to be retained the latter portion is wound upon the spool 37 whereas the portion to be delivered is projected through the slot 12, the projecting portion being detached and given to the customer as a receipt or ticket to show the amount of motor fuel, or lubricating oil delivered.

15 Resilient guides 62 project inwardly from the front of the casing in line with the delivery slot 12 and serve to direct the strip 40 through the delivery slot. A fixed guide 63 projects outwardly from the casing and receives the projecting portion of the strip. 20 A resilient guide 64 is disposed above the rigid guide 63 and the projecting portion of the strip 40 passes between the guides 63 and 64. A pressure member 65 of cam formation is mounted above the resilient guide 25 64 and is adapted to be operated to move the guide 64 to clamp the projecting portion between the guides 63 and 64, so that the projecting portion of the strip corresponding to the sales strip ticket, or receipt, may be conveniently severed or torn from the main portion of the strip. A crank handle 66 connected with the pressure member 65 provides 30 convenient means for operating the latter when it is required to clamp the strip between the guides 63 and 64.

35 When the door 11 is released and moved aside to admit of access to the interior of the casing 10 a strip roll may be placed in position and the strip adjusted between the feed roll 27 and the retaining roll represented by the shaft 35 and grooved rollers 42. An end portion of the strip 40 may be passed over the guide roll 55 and engaged 40 with the rewinding roll 37 and the end portion of the strip corresponding to the sales check may be passed between the guides 62 through the delivery slot 12 and between the guides 63 and 64. After the strip has thus 45 been adjusted, the door 11 is closed and locked, thereby preventing any tampering with the mechanism. The strip 40 has longitudinal portions similarly designated to indicate units of measure, such as gallons, or quarts, depending upon the particular application of the mechanism. When the

50 pump is operated the recording and sales check mechanism is correspondingly actuated, and a portion of the strip 40 is delivered through the slot 12 and a portion wound upon the roll 37 corresponding to the amount of motor fuel, oil, or the like, delivered. The drive belt 36, transmitting motion from the feed roll shaft 26 to the rewinding spool 37 preferably consists of a wire coil, whereby the same is at all times 55 under tension and provision had for slippage as the relative diameter of the rolls or spool varies. When the door 11 is moved to open position and the shaft 17 is uncoupled from the pump operating shaft 59 the entire mechanism may be removed from the casing 10 by detaching the plate or frame 14 from the blocks 13 and withdrawing the said plate or frame with the parts attached thereto through the open side of the casing. In this manner the mechanism may be readily 60 inspected, or cleaned, or repaired, and easily and quickly placed in position.

Having thus described the invention, we claim:

1. A recording and sales check mechanism for fluid dispensing pumps, the same comprising a feed mechanism for the recording and sales check strip adapted to be coupled to the pump operating mechanism to be actuated thereby, means for dividing said strip longitudinally, a spool for rewinding a divided portion of the strip and a drive belt connecting the rewinding spool with the strip feeding mechanism and normally maintaining a tension and providing for slippage due to variation in the diameter of the rewinding spool.

2. A recording and sales check mechanism for fluid dispensing pumps, the same comprising a feed roll for the recording and sales check strip adapted to be coupled to the operating mechanism of the pump to be actuated thereby and provided with teeth to make positive engagement with said strip, a pressure roll coacting with the feed roll and grooved to receive the teeth thereof, a rotary cutter carried by the pressure roll, connecting means between the feed and pressure rolls, means for delivering a portion of the said strip and means for rewinding the other portion of the strip, and coupled to the feed roll to be actuated thereby.

3. In a recording and sales check mechanism for fluid dispensing pumps, the combination of a shaft adapted to be coupled to the operating mechanism of the pump, a plate rotatable with said shaft, a spur gear loose upon the shaft, pawls mounted upon the plate and adapted to coact with said spur gear to impart rotary movement thereto in one direction, a strip feed roll geared to the said spur gear, a pressure roll coacting with the feed roll and geared thereto, and a strip cutter mounted upon the pres-

sure roll and adapted to coact with the feed roll for dividing the strip longitudinally.

4. In a recording and sales check mechanism for fluid dispensing pumps, the combination of a casing having a discharge slot for the sales check strip, mechanism within the casing coupled to the pump operating mechanism to be actuated thereby and including means for feeding the strip through the said discharge slot, guide members exterior to the casing in line with the discharge slot thereof to receive between them the projecting end of the strip, and independent pressure means for bringing the guide members together to clamp the projecting end of the strip to facilitate the severing thereof.

5. In recording and sales check mechanism for fluid dispensing pumps, the same comprising a casing having a discharge slot for the sales check strip, mechanism within the casing adapted to be coupled to the pump operating mechanism to be actuated thereby, resilient guides projecting inward from the casing in line with the discharge slot thereof, other guide means projecting

outwardly from the casing in line with the discharge slot, and means for pressing the outer guide means together to clamp the projecting portion of the sales check strip.

6. A recording and sales check mechanism for fluid dispensing pumps, the same comprising a casing having a discharge slot, a feed roll within the casing for advancing the recording and sales check strip, operating means between the feed roll and the pump operating mechanism including a ratchet mechanism, a pressure roll associated with the feed roll and including a rotary cutter for dividing the said strip longitudinally, a roll within the casing for rewinding a divided portion of the strip, the other portion of the strip being delivered through the said discharge slot, means mounted upon the casing for clamping the projecting end of the sales check strip, and a supporting frame for the operating parts removably fitted within the casing.

In testimony whereof we affix our signatures.

ARTHUR R. MASON. [L. S.]
OTTO C. FAILING. [L. S.]
